UNITED STATES PATENT OFFICE.

LUCIAN B. ROBB, OF CINCINNATI, OHIO.

DRY CLOSET.

SPECIFICATION forming part of Letters Patent No. 376,550, dated January 17, 1888.

Application filed May 19, 1887. Serial No. 238,712. (No model.)

To all whom it may concern:

Be it known that I, LUCIAN B. ROBB, a citizen of the United States, residing at Cincinnati, in the county of Hamilton, State of Ohio, 5 have invented certain new and useful Improvements in Dry Closets, of which the following is a specification, reference being had therein to the accompanying drawings.

This invention relates to those closets which 10 are constructed in such a manner as to permit the use of fire for drying or entirely consuming alvine discharges or other offensive or noxious substances; and the first part of my improvements comprises a sealed deposit-chamber 15 that receives these substances, and also serves as the oven or crematory of the apparatus. The walls of this chamber are preferably of masonry, and are completely closed or sealed on all sides, except where a removable 20 tile or other cover is temporarily cemented in place, and where a single shaft or pipe proceeds from the upper part of said chamber. One or more privy-boxes communicate directly with this single shaft, and a forced draft 25 is maintained in the latter by connecting the smoke-pipe of a cooking or heating stove or steam-boiler therewith, by which arrangement said shaft is caused to perform the threefold duty of ventilator, soil-pipe, and chimney, it 30 being understood that the aforesaid removable slab or tile is always to remain in place, except when the oven is fixed up to consume the excrements deposited therein, as hereinafter more fully described.

35 The second part of my improvements consists in filling the lower portion of this sealed chamber with a non-combustible absorbent-bed that retains the urine and other waste fluids, a furnace being inclosed by this bed, in 40 order that the contents of the latter may be readily evaporated at suitable intervals, as hereinafter more fully described.

The third part of my improvements consists 45 in making the walls of said sealed chamber double, with an air-space between them, said air-space being provided with openings that communicate with the interior of the chamber, in order that any fumes or vapors which may pass through the inner wall can be drawn off 50 at the ventilating-shaft of the closet, as hereinafter more fully described.

The fourth part of my improvements com-

prises a novel construction of privy-boxes to be used with cremating-closets, each seat being provided with a curved discharge-chute, a 55 scraper, and a valve or flap, as hereinafter more fully described.

In the annexed drawings, Figure 1 is a partly-sectional elevation of my improved cremating-closet, a fire being seen in the furnace of the 60 same. Fig. 2 is a transverse section of the deposit-chamber and its inclosed furnace. Fig. 3 is an enlarged vertical section through one of the privy-boxes. Fig. 4 is a horizontal section of said box.

65 The sealed deposit-chamber A, which is of any suitable size and shape, is usually built of brick, being composed of an outer wall, B, and an inner wall, B', which inclose an air-space, C. This air-space surrounds the four sides of 70 chamber A, and has one or more openings, c, leading into said chamber, the lower portion of which latter contains the furnace D. This furnace projects through one end or side of chamber A, and has a fire-door, E, bridge-wall d, and smoke-pipe e, whose upper end is adapted to discharge directly into said chamber. F and f are bearers for said furnace and pipe.

75 The bottom of chamber A may be level, as 80 seen in Fig. 2; but I prefer sloping it toward the center, as represented in Fig. 1, a drain-pipe, G, being situated at the lowest point of said bottom, which pipe is guarded by a strainer, g.

85 H represents a bed composed of sand or other cheap non-combustible absorbent, which bed is carried up a few inches above the top of the furnace D and surrounds the sides of the same, as seen in Fig. 2.

90 The ventilating shaft I is carried directly up from the sealed chamber A, and is of such a capacity as to perform the threefold duty of ventilator, soil-pipe, and chimney for the dwelling-house or factory in which the closet 95 is situated. When located within a dwelling, the draft of this shaft may be maintained by connecting the pipe J of a heating or cooking stove, j, therewith; but when said shaft is applied to a factory the smoke-pipe from the boiler may be attached thereto. Communicating with this combined ventilator, soil-pipe, and chimney are the privy-boxes K K', of which as many may be used as circum-

stances suggest. The details of these boxes are more clearly seen in Figs. 3 and 4, reference to which illustrations shows that the box is adapted to fit snugly against the chimney-wall, and has at top a customary seat, L, to which a solid lid, M, is hinged at l, while the lower portion of said box takes the shape of a concave discharge-chute, N, the latter being concentric with a shaft or journal bearing, O. 5 This shaft is arranged horizontally across the box K, and carries a solid flap or valve, P, and a curved bar or bow, R, that constitutes the scraper for the chute. Furthermore, this shaft carries a handle or crank, S, that may 10 be operated by the person using the closet; or said crank may be so coupled to the lid M as to be automatic in its movements, as the exact method of actuating the valve and scraper constitutes no part of my invention. 15 T in Fig. 1 is a frame passing through the walls B B', the inner end of said frame having a tile, slab, or plate, t, temporarily cemented therein.

The operation of this form of cremating- 20 closet is as follows: The fire door E and slab t are first closed up tightly to prevent air entering the chamber A, and the various lids M are shut down upon the seats L of the privy-boxes K, and simultaneous with this closure 25 of said lids the shaft O is turned, either by hand or mechanically, but preferably the latter, until the valve P and scraper R assume the position indicated by the dotted lines p r in Fig. 3. It is evident that the closed valve P 30 prevents the escape into the room of any odors from the chamber A or smoke from the pipe J in case the closet should be situated in an upper story.

To use either of the closets, the lid M is 35 opened, as seen in Fig. 3, and the valve P is turned up to an erect position, which act causes the scraper R to be about horizontal, in order that the excrements may drop through this ring-scraper and lodge upon the concave discharge-chute N. When the person is done 40 with the closet, the lid thereof is closed and valve P is again turned down to its normal or horizontal position, during which act the scraper R rakes the excrements from off the 45 chute N and precipitates them down the soil-pipe or chimney I into the deposit-chamber A. The excrements, paper, and other litter gradually accumulate upon the sand-bed H, while the latter absorbs the urine or other 50 fluids, and thus prevents the contents of the chamber assuming a semi-liquid condition. When this bed becomes thoroughly saturated 55 with urine and is unable to absorb any more, the fluid then simply percolates through the sand and is carried off at the drain-pipe G. As soon as the chamber is sufficiently full, all 60 the lids M are closed and a fire is started in the furnace D, for the purpose of evaporating the urine or other fluids from the bed H, and causing a preliminary drying of the excrements, 65 which drying is effected in part by the heat

that passes through the sand and in part by the products of combustion that escape from the smoke-pipe e directly into the chamber. In some closets this drying of the excrements 70 or other offensive or noxious substances by the heat from the furnace may be all that is needed; but in other cases it may be desired to consume them to ashes and then remove the latter bodily from the chamber. To accomplish this result, the slab t is knocked out as soon as the excrements are sufficiently dried, and the mass is then saturated with coal-oil and ignited; or a wood or coal fire is built directly upon said mass, and is maintained until the excrements are reduced to ashes. The 75 ashes are then drawn off from the surface of bed H through the opening or easing T, slab t is again cemented in place, and the chamber is at once sealed up ready for use. During 80 this drying or burning out of the chamber the fire from the same passes directly up the shaft I, and thus consumes any fecal matter adhering to the walls of the same, and therefore the entire closet is entirely and economically 85 purified without endangering the house or causing any nuisance in the neighborhood.

As bricks are more or less porous, there is danger of the urine either filtering through an ordinary wall or causing its exterior surface 90 to sweat and emit a very disagreeable odor, which serious objection is entirely obviated by using the two walls B B', with an air-space, C, between them. This air-space collects all such odors and discharges them through the 95 opening e into the upper part of deposit-chamber A, and, as the kitchen-stove j is almost constantly creating a draft up the shaft I, it is evident that the entire closet is thus ventilated 100 without requiring special attention. It is also 105 evident that the daily use of the closet causes more or less soot to be loosened from the chimney and fall down into the chamber A. The creosote of the soot thus mixes with the excrements and acts as a powerful deodorizer and 110 antiseptic, which materially assists in keeping the chamber pure.

In this specification the word "sealed" is not to be construed as referring to a chamber that is absolutely air-tight, nor one that can 115 never be opened; but said word is used to indicate a chamber that is normally shut or closed on all sides, except where a single shaft or pipe communicates therewith, and is capable of being opened when occasion requires 120 to permit of the excreta, &c., being dried or consumed.

Finally, I am aware that it is not new to construct fire or crematory closets with a down- 125 cast shaft that admits fresh air to the deposit-chamber and an upcast shaft that draws off the foul air. Therefore I expressly disclaim such double-shafted closets, inasmuch as they are liable at times to induce return-drafts of air and thereby discharge the offensive vapors 130 into the house.

I claim as my invention—

1. The combination, in a cremating-closet, of a sealed deposit-chamber and a single shaft proceeding from its upper part, which shaft performs the threefold duty of ventilator, soil-pipe, and chimney, substantially as herein described.

2. The combination, in a cremating-closet, of a sealed deposit-chamber, a non-combustible absorbent bed, a furnace, a smoke-pipe, and a single shaft proceeding from the upper part of said chamber, within which latter the furnace is situated and is surrounded or partially surrounded by said bed, the smoke-pipe being arranged to discharge into said chamber, and the single shaft serving as the ventilator, soil-pipe, and chimney of the closet, substantially as herein described.

3. The combination, in a cremating-closet, of the deposit-chamber A, surrounded by outer walls, B, inner walls, B', and air-space C, openings *cc* being provided in said inner walls, and a single shaft, I, being applied to the upper part of said chamber in order that the air-

space C may be ventilated through said openings and shaft, as herein described.

4. The combination, in a cremating-closet, of a sealed deposit-chamber having means for drying or burning the excreta collected therein, and a single shaft proceeding from said chamber, which shaft has a series of privy-boxes attached thereto at different levels and has the smoke-pipe of a cooking, heating, or steam apparatus leading into it, for the purpose described.

5. A cremating-closet provided with a privy-box having a valve, P, rigidly connected to the bow-scraper R, which latter rakes the excreta from off the concave discharge-chute N of said box, as herein described.

In testimony whereof I affix my signature in presence of two witnesses.

LUCIAN B. ROBB.

Witnesses:

JAMES H. LAYMAN,
S. S. CARPENTER.

It is hereby certified that in Letters Patent No. 376,550, granted January 17, 1888, upon the application of Lucian B. Robb, of Cincinnati, Ohio, for an improvement in "Dry Closets," an error appears in the printed specification requiring correction as follows: In line 32, page 1, the word "fixed" should have been printed *fired*; and that the said Letters Patent should be read with this correction therein that the same may conform to the record of the case in the Patent Office.

Signed, countersigned, and sealed this 24th day of January, A. D. 1888.
